UNITED STATES PATENT OFFICE.

DARIUS W. HARRIS, OF FISKDALE, MASSACHUSETTS, ASSIGNOR TO THE SNELL MANUFACTURING COMPANY, OF SAME PLACE.

METAL DIE FOR MAKING AUGERS.

SPECIFICATION forming part of Letters Patent No. 276,033, dated April 17, 1883.

Application filed September 30, 1882. (No model.)

To all whom it may concern:

Be it known that I, DARIUS W. HARRIS, a citizen of the United States, residing at Fiskdale, in the county of Worcester and State of Massachusetts, have invented certain new and useful Improvements on Metal Dies for Dropping or Heading Augers, Auger-Bits, and other Boring-Tools, of which the following is a specification.

10 My invention relates to an improvement on the die described in United States Letters Patent No. 151,325, granted to Wm. Tucker, May 26, 1874, said die being adapted to be clamped or otherwise fastened to the bed of a drop-press, and to receive a bit or other boring-tool to be headed or "dropped," said heading or "dropping" being then effected by the descent of the drop or hammer, carrying a suitable die for forming the screw-point and spurs. The lower die is provided with suitable projections to enable it to produce the side cuts on and give the requisite inside impression to the end or head of the auger; and my improvement particularly relates to the 25 strengthening of these projecting parts of the lower die by forming a ridge extending from and forming an abutment for each projection on the two-part lower die, in the manner hereinafter more fully set forth.

30 In the accompanying drawings, Figure 1 is a front elevation of one member of the two-part lower die embodying my invention. Fig. 2 is a plan of the same, showing a bit or auger in place therein. Fig. 3 is a vertical section thereof on the line 3 3, Fig. 1, looking to the left. Fig. 4 is a section on the same line, looking to the right.

The blocks of metal F, forming the stocks of the lower dies, and having suitable crimps, 40 forming a spiral bore, z, to receive the auger or bit, are clamped or secured in any manner to the bed of a drop-press, so as to be capable of clamping between them the twisted auger X, to be operated upon. Undercut grooves f

are formed in the stocks F, within which 45 grooves slide guides g on the under surface of the hard-metal dies G. These dies, when in position, are firmly secured to the stock F by screws H. The adjoining faces of the dies G have vertical concavities provided with the 50 ordinary crimps, forming a continuation of the bore z for clamping the auger. The top of the dies G is provided with segmental projections or anvils y, terminating the twists, the same being concentric with the bore z, and of the 55 height of the required side cuts of the auger. The dies, as provided with these projections, are adapted to give the required inside impression to the end or head of the auger, the impression on the outer side or extreme end 60 of the auger being made by an upper die carried by the drop or hammer of the press, in manner substantially as described in the patent before referred to.

To render the projections or anvils y stronger 65 and enable them to resist the crushing effect of the drop is the object of my invention, and this object I accomplish effectually by making the dies G with ridges or abutments R, extending from the projections y across or partially across the face of the die. These ridges are made of sufficient height to serve as strong 70 abutments for the anvils y, but are not made high enough to interfere with the descent of the drop or formation of the side cuts of the 75 auger.

Having thus described my invention, the following is what I claim as new therein:

The dies G, adapted to hold and form the heads of augers, auger-bits, or other boring-tools, and having projections y and abutments R for strengthening the same, substantially as described.

DARIUS W. HARRIS.
